UNITED STATES PATENT OFFICE.

BARON HENRY SCOTFORD, OF ATLANTIC CITY, NEW JERSEY.

DESIGN FOR A DRESS.

60,269.

Specification for Design.

Patented Jan. 17, 1922.

Application filed July 30, 1920. Serial No. 400,248. Term of patent 3½ years.

To all whom it may concern:

Be it known that I, BARON HENRY SCOTFORD, a citizen of the United States, residing at Atlantic City, in the county of Atlantic and State of New Jersey, have invented a new, original, and ornamental Design for a Dress, of which the following is a specification, reference being had to the accompanying drawing, forming part thereof.

The figure is a plan view of a dress, showing my new design.

I claim:

The ornamental design for a dress, as shown.

BARON HENRY SCOTFORD.
